United States Patent Office

Des. 221,587
Patented Aug. 24, 1971

221,587

HIGH FREQUENCY PROBE

Edward E. Aslan, Plainview, N.Y., assignor to The Norda
Microwave Corporation, Plainview, N.Y.

Filed Mar. 23, 1970, Ser. No. 21,999

Term of patent 14 years

Int. Cl. D10—99

U.S. Cl. D52—6

FIG. 1

FIG. 2

FIG. 3

FIG. 4

FIG. 1 is a front perspective view of a high frequency probe embodying my new design;

FIG. 2 is a front elevation view of the probe illustrated in FIG. 1;

FIG. 3 is a front perspective view of a second modified high frequency probe embodying my new design; and

FIG. 4 is a front elevation view of the probe shown in FIG. 3.

I claim:

The ornamental design for a high frequency probe, as shown and described.
